TRANSMISSION SYSTEM

Felix Strecker, Berlin-Siemensstadt, and Hermann Kimmel, Berlin-Charlottenburg, Germany, assignors to Siemens & Halske Aktiengesellschaft, Berlin, Germany, a corporation of Germany

Application July 14, 1936, Serial No. 90,472
In Germany July 27, 1935

6 Claims. (Cl. 179—170)

This invention relates to an improved transmission system comprising amplifiers.

In transmission and repeating systems equipped with echo killers or suppressors, there exists the risk of a feedback being produced when the system is not acted upon by the voice. The said feedback may be caused by disturbing or stray currents which happen to penetrate the system. Inasmuch as these currents, as a general rule, are so feeble that the echo suppressor device will not be caused to operate instantaneously, a gradual building up by amplification of the stray currents will be occasioned if the aggregate damping of the feedback path is negative. When the amplitude has reached an adequately large value, the suppressor means will be caused to operate and to thereby interrupt the feedback path. The same process will be repeated again and again, that is to say, the echo suppressors are continually operated and stopped, and this is attended with a disagreeable background noise in the line.

Now, it is known from the earlier art that these echo suppressors may be combined with feedback stoppers in order that, also in the absence of voice or speech actions, at least one sense of transmission may be blocked. While it is true that in this manner feedbacks are preventable, there results this drawback that, because of the finite time of response, the beginnings of signals or even entire signals which are not yet strong enough in order to cause discontinuance of the blocking produced by the feedback block, may be suppressed. Inasmuch as this action, under certain circumstances, may recur with the beginning of each word, it is liable to become extremely troublesome.

It has also been suggested in the prior art to insert in the feedback path resistances whose action is a function of the amplitude, and which will suppress the amplitude below a certain limiting value. If the said limiting value is chosen above the disturbing or stray amplitudes that may normally be expected, the risk of the arising of spurious feedbacks in the absence of voice actions is diminshable with means of the said sort.

Now, the present invention is concerned with a similar means adapted to secure the stability of operation when the system is not subject to voice actions, without, however, involving the drawback of requiring the insertion of distinct additional non-linear resistances. The desired success, according to this invention, is attained by the insertion and connection of C-type amplifiers in the feedback path. Inasmuch as these

amplifiers may at the same time be used for voice amplification and not merely for blocking purposes, their use represents a progress of the art in contrast to the above-mentioned nonlinear resistances which introduce additional attenuation in the system.

This invention will best be understood by referring to the accompanying drawing, in which:

Fig. 1 illustrates a curve of the tubes in a push-pull C-type amplifier;

Fig. 2 illustrates a curve of the tubes in a push-pull C-type amplifier having the working point shifted in a more negative direction than that shown in Fig. 1;

Fig. 3 is a schematic diagram of the circuit of this invention.

The grid biasing voltage of C-type amplifiers, as is well known, is chosen in such a way that the working point lies outside the range in which plate current flows. Fig. 1, for instance, shows the characteristics *a* and *b* of the tubes of a push-pull C-type amplifier. They illustrate the dependence of the plate current *ia* upon the grid potential *eg*. The working point is indicated by *A*. Now, an amplifier operated with such a biasing potential possesses the property to completely suppress currents whose amplitudes do not go beyond the value *c*. Larger amplitudes, say, amplitudes *d* which essentially exceed the value *c*, are handled by the C-type amplifier. If the amplifier is to be made impervious also for larger amplitudes with a view to insure echo killing, then the working point for each tube must be shifted a corresponding distance in the negative sense as indicated in Fig. 2. It will be seen that also amplitudes equal to *d* cause no change in the plate current.

It will be noted from an examination of Fig. 1, that when C-type amplifiers are used in the present connection, there happens a certain non-linear distortion; and the latter will be so much more marked, the more negative the biasing of the amplifiers, and the smaller the transmitted amplitudes in comparison with the biasing potential. Hence, in choosing the biasing potential care must be taken so that the same will not be unduly or unnecessarily high. Inasmuch as the size of the biasing voltage, in downward direction, is limited by the noise level, the case may arise where the biasing voltage must be chosen higher than what would be permissible from the viewpoint of non-linear distortions. Now, in order that undistorted and faithful transmission may be secured also under these circumstances, this invention provides ways and means of a nature so that, in the presence of

voice transmission, the C-type amplifier in the transmitting sense by suitable circuit modifications and change of its grid potential, is altered so as to act as an A-type or a B-type amplifier. 5 However, such a circuit change, if the stability of the feed-back circuit is not to be endangered, should be accomplished only when the opposite direction has already been rendered impervious by the operation of the echo suppressor device. 10 For the identical reasons it is recommendable that when the A or B-type amplifier after discontinuance of the voice transmission, is restored again to a C-type amplifier, this change should be accomplished with less retardation or lag than 15 the lag with which the blocking is rendered inoperative in the contrary direction. The change in the voltage is effected in both instances preferably by the aid of a mechanical relay or other known circuit means designed to impress upon and re- 20 move from the grid a definite and fixed amount of potential.

Fig. 3 shows an exemplified embodiment of the basic idea of the invention in schematic form. Between the two lines L_1 and L_2 , by the aid of 25 balanced differential (or three-coil) transformers and the simulation or balancing means N_1 and N_2 is connected a two-wire intermediate telephone or through-line repeater. The latter comprises, in each sense or direction of transmission, amplifiers V_1 and V_2 which are placed ahead of the push-pull C-type amplifiers C_1 and C_2 . Above these latter are branched off amplifying rectifiers G_1 and G_2 whose direct current voltages serve for the purpose of shifting the grid potential of the 30 C-type amplifier of the opposite direction of transmission. By the relays R_1 and R_2 which are also fed from the output current of the said rectifiers G_1 and G_2 , the above-mentioned change of the C-type amplifiers into B or A-amplifiers 35 is indicated. These relays which work with retarded response and rapid drop may be designed so that, for instance, part of the grid biasing voltage impressed upon the C-type amplifiers is short-circuited for the purpose of effecting their 40 being changed into A or B amplifiers. In this manner it will be an easy matter to shift the working point of the amplifiers a certain pre-arranged amount. It will be evident that, within 45 the scope and spirit of this invention, it is possible also to resort to other ways and means adapted to insure a prefixed and accurate shift of potential, say, circuit schemes comprising glow-discharge or glow-tubes.

50 The use of the idea underlying this invention in connection with four-wire amplifiers is analogous and similar to the use thereof with two-wire amplifiers as before described.

55 What is claimed is:

60 1. A transmission system for the suppression of echos comprising two single one way transmission paths for transmission of signals in opposite directions connected in series and coupled between two separate incoming lines, a separate 65 amplifier connected in series with opposed outputs in each transmission path and ahead of a push pull amplifier of the C-type whose grid bias voltage is chosen in such a way that the working point lies outside the range in which the 70 plate current flows, said push pull amplifier of the C-type connected intermediate said incoming lines to prevent feedback in the absence of voice impulse action upon said system, a rectifier circuit whose D-C output voltage serves to shift the 75 grid potential of said push pull amplifier

branched from the output of said push pull amplifier with its output connected to the push-pull amplifier in the opposite path in such a manner as to render it inoperative as a C-type amplifier. 5

2. A transmission system for the suppression of echos comprising two single one way transmission paths for transmission of signals in opposite directions connected in series and coupled between two separate incoming lines, a separate amplifier connected in series with opposed outputs in each transmission path and ahead of a push-pull amplifier of the C-type whose grid bias voltage is chosen in such a way that the working point lies outside the range in which the plate current flows, said push pull amplifier of the 15 C-type connected intermediate said incoming lines to prevent feedback in the absence of voice action upon said system, a rectifier circuit whose D-C output voltage serves to shift the grid potential of said push pull amplifier branched from the output of said push pull amplifier with its output connected to the push-pull amplifier in the opposite path in such a manner as to render it inoperative as a C-type amplifier, and a relay system connected to the output of said rectifier so that the echo suppression is effected by a shift of grid potential in said C-type push pull amplifiers. 20

3. A transmission system for the suppression of echos comprising two single one way transmission paths for transmission of signals in opposite directions connected in series and coupled between two separate incoming lines, a separate amplifier connected in series with opposed outputs in each transmission path and ahead of a push pull amplifier of the C-type whose grid bias voltage is chosen in such a way that the working point lies outside the range in which the plate current flows, said push pull amplifier of the C-type connected intermediate said incoming lines to prevent feedback in the absence of voice action upon said system, a rectifier circuit whose D-C output voltage serves to shift the grid potential of said push pull amplifier branched from the output of said push pull amplifier with its output connected to the push-pull amplifier in the opposite path in such a manner as to render it inoperative as a C-type amplifier and means to change the working voltages of each of the push pull C-type amplifiers located in the direction acted upon by the voice impulses so as to substantially decrease the negative bias of said push-pull amplifier. 30

4. A system according to claim 3, with the characteristic feature that the change of the negative bias on said push-pull amplifiers is produced with time-lag devices only when the opposite direction of transmission has been blocked by said rectifiers. 35

5. A system according to claim 3, with the characteristic feature that upon discontinuance of the voice impulses the change from an amplifier having a decreased negative bias into a C-type amplifier is effected more rapidly than the discontinuance of the signal impulses in the path of transmission in an opposite direction. 40

6. A system according to claim 3, with the characteristic feature that the restoration of the C-type amplifier into an amplifier having a decreased negative bias is accomplished by means of a mechanical relay which is arranged by being connected in circuit with the output of said rectifier to produce the requisite change in potential. 45
